UNITED STATES PATENT OFFICE.

PAUL THORBJORNSEN, OF CHICAGO, ILLINOIS, ASSIGNOR TO S. KARPEN & BROTHERS,
OF CHICAGO, ILLINOIS, A CORPORATION OF WEST VIRGINIA.

SOFA-BED.

946,887.

Specification of Letters Patent. Patented Jan. 18, 1910.

Application filed July 27, 1909. Serial No. 509,790.

To all whom it may concern:

Be it known that I, PAUL THORBJORNSEN, a subject of the King of Norway, residing at Chicago, in the county of Cook and State 5 of Illinois, have invented a new and useful Improvement in Sofa-Beds, of which the following is a specification.

My invention relates particularly to combination sofas and beds, or combination couches and beds, in which a foldable mattress-frame is normally housed within the main frame beneath the seat of the sofa and equipped with a flexible bed-bottom, or wire mattress, the parts being so related as to afford room between the sections of the folded mattress for the bed, *i. e.*, the mattress-pad, bed linen and covers.

My primary object is to provide an improved construction of the character indicated having the attributes of simplicity and durability and which is readily convertible from sofa form to bed form and vice versa, said construction being capable of being manufactured at very moderate cost, but nevertheless affording a very satisfactory sofa in one form, and a very comfortable bed when in another form.

The invention is illustrated in its preferred embodiment in the accompanying 30 drawings, in which—

Figure 1 represents a sectional view of my improved sofa-bed in the open or bed position; Fig. 2, a similar sectional view showing the structure in closed condition; Fig. 3, an enlarged detail sectional view 35 taken as indicated at line 3 of Fig. 1; Fig. 4, a perspective view showing the hinge-members employed to connect the front portion of the sofa-seat with the main frame; Fig. 5, a broken horizontal sectional view 40 showing the structure in bed form; and Fig. 6, a sectional view taken as indicated at line 6 of Fig. 1.

In the construction illustrated, A represents a main frame; B, a stationary back supported by the end-standards of the main frame; C, a seat pivotally connected at its front portion with the front portion of the main frame; and D, a foldable bed normally 50 housed in folded condition within the main frame beneath the seat C.

The frame A may be of any suitable construction. As shown, it comprises end-standards 1; a front connecting member 2, and a rear connecting member 3. The end-

standards 1 usually are of ornamental form and shaped at their upper ends to provide arms 4 for the sofa.

The back B is disposed between the rear upper portions of the end-standards 1, being rigidly connected therewith in any suitable manner.

The seat C comprises a frame 5 and cushion 6. The front portion of the frame 5 is provided, at the ends of the frame, with hinge members 7 having trunnions 8. Secured to the inner surfaces of the end-standards 1 are clips, or hinge members, 9 having in-struck bosses 10 provided with vertical slots 11 adapted to receive the trunnions 8. The slots 11 are open at their upper ends, so that the seat may be lifted out of its bearings.

The bed-frame D comprises a front section 12; a rear section 13; and an intermediate section 14. The section 12 normally depends, when the structure is in the sofa form, beneath the seat-frame, being rigidly attached thereto. Said section comprises end members 15 which are preferably of angle-bar form. The end members 16 of the seat-frame 5 have downturned extensions 17 to which the members 15 are secured. An angle-bar truss-member 18 is secured to the rear lower corner of the seat frame and has at its extremities depending arms 19 connected with the extremities of the members 15. The front ends of the downward extensions 17 are connected by braces 20 with the main portion of the seat-frame 5. The intermediate bed-section 14 comprises end members 21 of angle-bar form having their upper or front extremities connected, by pivots 22, with the adjacent extremities of the members 15; and a truss 23 having arms 24 secured to the other extremities of the members 21. Braces 25 connect the arms 24 with the intermediate portions of the members 21. The rear bed-section 13 is preferably a U-shaped member having a longitudinal web 26 and forwardly-extending end members, or arms, 27. This U-shaped member is preferably of angle-bar construction. The extremities of the arms 27 are connected, by bolts 28, with the adjacent extremities of the members 21 and the extremities of the arms 24. The inner surfaces of the end-standards 1 of the main frame are equipped with pivot-blocks 29 to which are pivotally joined links 30 whose

free ends are provided with channels, or guides, 31 adapted to receive the down-turned flanges of the end members 27 of the rear bed-section, as will be clearly understood from Fig. 3. Links 32 are connected, at their rear ends, by pivots 33, with the links 30 near the free ends thereof, and are connected, at their front ends, by pivots, or bolts, 34, with arms 35 rigidly secured to the 10 extremities of the end members 27 of the rear bed-section.

The upper edge of the front connecting member 2 of the main frame is preferably rounded, or beveled, as indicated at 36. 15 Said upper edge affords a bearing for the truss 23 of the intermediate bed-section when the bed is in the extended position, and the purpose of the bevel 36 is to enable the truss 23 to move properly onto its bearing when 20 the structure is converted from sofa form to bed form. Said truss is provided with projections 36^a which rest upon the inverted seat-frame. The bearings 36^a are adapted to rest with certainty on the seat-frame, even 25 though great accuracy of construction is not attained in the manufacture of the structure.

Connected with the end members of the three bed sections is a flexible bed-bottom, 30 or wire mattress, 37, adapted to fold and unfold with the folding and unfolding of the bed frame. At the extremities of the front and rear bed-sections are members, or standards, 38, adapted to confine the bed- 35 pad, or mattress proper, longitudinally. In Fig. 2, the bedding 39 is indicated in the folded condition by dotted lines. The inner surfaces of the lower portions of the end standards 1 of the main frame are 40 equipped with stops 40 adapted to support the links 30 in the folded condition of the structure. Any suitable means (not shown) may be employed for securing the bedding to the bed-frame.

45 The operation will be readily understood from the foregoing description. The bed is made up while the structure is in the open position shown in Fig. 1, and the structure is then converted to sofa form by swinging the seat rearwardly to the position shown in Fig. 2. When the seat is swung to the folded position, the front bed-section, which is rigidly attached to the seat, is carried to the depending position shown in Fig. 2, 50 and the truss 23 of the intermediate section is carried off the bearing afforded by the upper edge of the front connecting member 2 of the main frame, and the rear bed-section is swung rearwardly and downwardly, in which movement it is carried by the links 33 whose upper ends slidably engage the end members of the rear bed-frame section and the links 32 which connect the links 30 with the arms 35 carried 55 by the front extremities of the end members 60

of the rear bed-section. Thus, the intermediate bed-section is carried bodily from its bearing on the main frame and lowered to the position shown in Fig. 2. In the reverse operation, the seat is swung from the position shown in Fig. 2 to the position shown in Fig. 1, carrying with it the front bed-section, which, in turn, actuates the intermediate and rear bed-sections, the links 30 swinging forwardly and upwardly and 75 carrying the rear bed-section.

The construction described is simple, durable and inexpensive, and affords a handsome and comfortable sofa when in the folded condition, and affords a comfortable bed 80 when in the open condition.

If desired, the seat and bed may be disconnected by removing the bolts 34 and lifting the trunnions 8 from the bearings 11. This is frequently of convenience in transporting the structure, as in moving from one 85 house to another.

The foregoing detailed description has been given for clearness of understanding only. Hence, no undue limitation should 90 be understood therefrom, but the appended claims should be construed as broadly as permissible in view of the prior art.

What I regard as new, and desire to secure by Letters Patent, is—

1. In a structure of the character set forth, the combination of a sofa-frame, a forwardly swinging seat connected at its front portion with said frame and adapted to assume an inverted position in front thereof, a bed-frame section rigidly suspended from said seat and disposed beneath the seat, an intermediate bed-section pivotally connected with said front section and equipped with a bearing member adapted to support it when the structure is in the open position, a rear bed-section pivotally connected with said intermediate bed-section, and links connected with the main frame and serving to lift the rear bed-section when the seat is swung to the 100 open position.

2. In a structure of the character set forth, the combination of a sofa-frame, a forwardly swinging seat connected with the front portion of said frame, rigidly carried members 115 depending from said seat, a front bed-section secured to said members, an intermediate bed-section equipped with a bearing member, a bearing on the structure adapted to support said bearing-member when the 120 structure is in the extended position, a rear bed-section pivotally connected with said intermediate bed-section, and links pivotally connected with the main frame and serving to carry said rear bed-section and to aid in 125 carrying said intermediate bed-section in the operation of unfolding and folding the seat.

3. In a structure of the character set forth, the combination of a main frame, a seat piv- 130

- totally connected at its front edge with the front portion of said frame, a rigidly carried front bed-section depending from said seat, an intermediate bed-section foldably connected with said front bed-section, a rear bed-section pivotally connected with said intermediate bed-section, and carrying means for the rear bed-section comprising a pair of links pivotally connected with the 5 main frame and slidably engaging the rear bed-section, and links pivotally connecting said first-named links with the front portion of the rear bed-section.
4. In a structure of the character set forth, 10 the combination of a main frame, a forwardly swinging seat pivotally connected therewith at its front portion, a depending, rigidly carried front bed-section attached to said seat, an intermediate bed-section comprising end members and a longitudinal truss having arms connected with said end members, a bearing near the front portion of said frame near the front edge of said seat adapted to support said truss when the 15 structure is in the extended position, a rear bed-section connected with said intermediate section and foldable with relation thereto, and carrying-links for the rear bed-section.
5. In a structure of the character set forth, 20 the combination of a sofa-frame having a front connecting member joining its end standards, a seat pivotally connected with said frame adjacent to the upper edge of said connecting member, rigidly attached 25 members depending from said seat, a front bed-section secured to said members, an intermediate bed-section pivotally connected to said front bed-section and having a truss 30 adapted to bear on said frame adjacent the upper edge of said front connecting member,
- a rear bed-section pivotally connected with said intermediate bed-section, and carrying links for the rear bed-section pivotally connected with said frame.
6. In a structure of the character set forth, 45 the combination of a main frame, a seat pivotally connected at its front portion to said frame, members rigidly carried by said seat and depending therefrom, a front bed-frame section secured to said members, an intermediate bed-frame section pivotally joined thereto, a rear bed-frame section pivotally connected with the intermediate bed-section, links pivotally connected with the lower portion of the main frame and having 50 their free ends extending rearwardly in the folded condition of the structure and slidably engaging the end members of the rear bed-section, and links pivotally connected with said first-named links near the free 55 ends thereof and pivotally connected with the front portions of the end members of the rear bed-sections.
7. In a structure of the character set forth, 60 the combination of a main frame, a seat, detachable pivot connections between the front portion of said seat and said main frame, a rigidly carried bed-frame section depending from said seat, an intermediate bed-section pivotally connected with the front bed-section, a rear bed-section pivotally connected with the intermediate bed-section, links for carrying the rear bed-section, and detachable connections for said links, whereby the 65 seat and bed may be disconnected from the main frame.
